POWER HAMMER

Ray Ferwerda, 1050 NW. 163rd Drive,
North Miami, Fla.
Filed Mar. 11, 1963, Ser. No. 264,253
4 Claims. (Cl. 173—105)

This invention relates to improvements in a power actuated blow delivering device of a very powerful character generally used as a power hammer or a power chisel, a power ram or the like.

One of the objects of the present invention is to provide a self-contained blow delivering device comprising a housing means with a tool carrying member extending into the housing means at one end, generally the lower end, and with an anvil lying inside of the housing and adapted to deliver a blow to a tool carrying member when struck by the hammer. The hammer is reciprocably mounted in the housing means for movement toward and away from the anvil, the blow being delivered by a powerful helical spring surrounding a hammer extension and engaged between the hammer and a portion of the housing means and always urging the hammer toward the anvil. Power means is carried by the housing means and constructed and arranged to engage the end of a hammer extension remote from the hammer, usually at the upper end thereof, and to lift the hammer so as to compress the spring and thereafter to suddenly release the hammer extension, whereby the spring then drives the hammer with great force against the anvil to deliver a blow to the tool.

Another object of the present invention is to provide the above described device in such simple form that there are few moving parts which are very rugged and adapted for a long period of efficient operation without repairs and adapted to deliver blows more powerful and more rapidly repeated than by presently known conventional methods.

Other objects and advantages of the present invention will be set forth in the accompanying drawings and specification and the essential features thereof will be summarized in the appended claims.

In the drawings—

FIG. 1 is a central sectional view through one embodiment of the device of this invention, together with means for mounting the device on a boom carrying vehicle adapted to hold and manipulate the blow actuating device;

FIG. 1A is a continuation of FIG. 1 at the lower end thereof showing the tool carrying member located below the line A indicated in both figures;

FIG. 2 is a sectional view, enlarged, taken along the line 2—2 of FIG. 1;

FIG. 3 is a sectional view taken along the line 3—3 of FIG. 1;

FIG. 4 is a fragmental sectional view taken along the line 4—4 of FIG. 2;

FIG. 5 is a fragmental sectional view taken along the line 5—5 of FIG. 2;

FIG. 6 is a sectional view taken along the line 6—6 of FIGS. 2 and 5; while

FIG. 7 is a view similar to a portion of FIG. 1, showing power means for turning the tool 46 responsive to remote control.

Referring to FIG. 1, this improved blow-delivering device is compactly assembled in connection with a housing means which comprises a cylindrical member 10 carrying at its upper end rigid therewith a flange 10a which is secured by means of screws or bolts 11 to a housing means head 12. The cylinder 10 is provided with a head member 13 at the lower end thereof welded to the cylinder 10 and having a central opening through which

2

enters an anvil shaft 14 coaxial with the cylinder 10 and carrying integral therewith at its upper end the anvil 14a. The anvil shaft 14 passes through a suitable bearing sleeve 15 which is rigidly connected to the head 13 and cylinder 10 by means of gussets 16 welded in place. Preferably, a recoil absorbing cushion 17 is provided in the form of a rubber doughnut surrounding the anvil shaft 14 and lying against the head 13. I have found that about 70 durometer rubber is satisfactory for this cushion. It will be noted that the anvil shaft 14 is freely slideable axially of the cylinder 10.

A hammer 18 is provided for delivering a blow to the anvil. This hammer is axially aligned with the anvil and is provided with a hammer extension 19 extending axially upwardly through the cylinder 10 and out the upper end thereof through a sleeve bearing 20 which is held in the proper position by means of a bearing cap 21 to which the bearing is welded and the cap in turn is secured to the lower wall of the housing head portion 12 by means of screws or bolts 22. An oil seal 20a prevents leakage of lubricant out of housing means 12. A powerful helical spring 23, approximately one foot in diameter and about three feet long (for a 4-ton blow) surrounds the hammer extension 19 within the cylinder 10 for compression between the hammer 18 and bearing cap 21 which lies against the lower wall of the housing head portion 12. Preferably each end of spring 23 engages a disc 23a of a hard, high abrasion resistant plastic backed up by a rubberlike cushion 23b.

Means is provided at the upper end of the hammer extension 19 whereby it may be lifted by power actuated means to provide periodic blows. This comprises a T-shape member 24, clearly shown in FIGS. 1, 2, 5 and 6, having a vertically extending central bore which fits on a reduced diameter portion 19a of the hammer extension which terminates at a shoulder 19b against which the T-shape member 24 rests. The upper portion of 19a is threaded and a nut 25 holds the member 24 in position. The T-shape member has laterally extending arms 24a on opposite sides thereof for the purpose of engagement by the device about to be described.

Preferably a space of a few thousandths of an inch is provided at 71, FIG. 6, between 19a and 24. Also, preferably a shoulder 72 keeps nut 25 from engaging tight against 24 leaving a few thousandths of an inch space at 73. This permits member 24 to accommodate to twisting of hammer extension 19 when spring 23 is stressed.

The power means for lifting the hammer extension comprises a hydraulic motor 26 bolted to the wall of the housing head means 12 and supplied with hydraulic power through flexible tubular connections 27 and 28 from any suitable source. This motor terminates in a drive shaft 29 which extends vertically downwardly into the housing means portion 12 and is provided with suitable bearings such as 30 carried by the bearing cap 31 and bearing 32 carried by the bearing cap 33 (FIG. 4). Rotatable with shaft 29 is a worm 34 which meshes with a cone drive worm gear 35 with a mechanical advantage of 20 to 1. Referring to FIGS. 2 and 4, the worm gear 35 is keyed to a shaft 36 which in turn is journaled in bearings 37 carried by suitable bearing caps 38 which are secured to the housing head 12. Keyed to the shaft 36 are a pair of pinions 39 each of which is aligned with a gear wheel 40 meshing with the pinions 39 and having a mechanical advantage of approximately 3 to 1. Each of the gear wheels 40 is keyed to a shaft 41 which is journaled in suitable bearings 42 which are carried by bearing caps 43 suitably attached to the housing head portion 12. A pair of cam rollers 44 are secured to each of the gear wheels 40 diametrically opposite each other by means of stub shafts 44a which extend through their respective gear wheels and are held in posi-

tion by nuts 45 and suitable lock washers. Each of the cam rollers 44 is rotatably mounted on its associated stub shaft. The cam rollers 44 on each gear wheel are aligned to engage beneath the opposite arms 24a of the T-member 24 so as to lift the hammer extension 19 and the hammer head 18. It will be noted in FIG. 1 that each cam roller 44 in the dotted line position of FIG. 1 engages beneath one of the T-shape arms 24a toward the left side thereof and lifts the T-shape member while the cam roller 44 moves through an arc of slightly more than 90° causing the cam roller to reach the dot-dash position of FIG. 1 after which it rolls out of contact with the arm 24a in the dot-dash position, thus releasing the arm suddenly so that it is urged downwardly impelled by spring 23 which has been compressed approximately 10 inches of its vertical length.

As shown in FIG. 1A, the anvil shaft 14 provides a tool carrying member. In this view the tool 46 has a central bore 46b provided axially of its upper end. Into this bore extends a projecting portion of shaft 14 which is held in position by means of one or more pins 47 embedded part way in the tool and part way in the shaft 14 and held in position by a sleeve 48 which embraces the shaft 14 at its lower end and rests upon the shoulder 46a of the tool. This prevents the escape of the attaching pins 47.

The tool shown at 46 is a chisel point tool for cracking rock, slate, concrete, masonry and many other construction materials. However, this tool might be a bull point for breaking up concrete and cement, or frost chisel for breaking away a frost layer of earth, or a tamper head for providing power compacting blows for tamping earth to solidify the same, or it might be a pile driver head for driving posts, piling and retainers into the ground. In other words, any suitable tool adapted to be driven by blows of the hammer 18 may be attached to this device.

Stop means is provided on the anvil shaft 14 to prevent it being driven up inside of the cylinder 10 so that the anvil head 14a always remains spaced from the blow delivering hammer 18. This stop is shown at 49 and comprises a split collar threaded on the shaft 14 and held in position by bolt 50. This collar will strike the lower end of the bearing sleeve 15 on the rebound after a blow is delivered and stop the upward motion of the anvil member 14a. Preferably, but not necessarily, a recoil spring 51 is provided surrounding the shaft 14 and held between the collar 49 and the bearing 15 to cushion the recoil of the bounce after the blow is delivered.

The collar 49 may be provided with means for preventing rotation of the tool 46 about its own axis if desired. I have shown in FIG. 1 a bar 52 rigidly welded to the housing cylinder 10 and extending freely through a hole 48a in the collar 49. This holds the tool oriented in a desired position.

As shown in FIGS. 1 and 3, means is provided for holding my improved blow delivering device and manipulating the same from a boom 53 which may be of any suitable type but is here shown as a telescopic boom of a vehicle shown in United States Patent No. 2,541,045, granted to Ray and Koop Ferwerda February 13, 1951. Bolted to the free end of this boom are a pair of spaced bearing caps 54, in which is journaled a shaft 55 which carries a crank arm 55a which in turn is pivotally connected to a clevis rod 56 which is controlled by means of a piston 57 reciprocable in a cylinder 58 secured to the boom 53 by means of hydraulic fluid or the like supplied through conduits 59. Movement of piston 57, which may be controlled from the operator's cab, will tilt the device about shaft pivot 55. Welded to the shaft 55 are a pair of spaced parallel ears 60 which in turn are welded to a sleeve 61 in which the cylinder 10 is held snugly but freely reciprocal in a vertical direction as blows are delivered. To hold the cylinder 10 from rotating in the sleeve 61, a vertical bar 62 is welded to the

flange 10a at the top and to a collar 63 at the bottom which in turn is bolted to the cylinder 10 by bolts 64. Parallel flanges 65 are welded to the sleeve 61 on opposite sides of the bar 62 and this prevents relative rotation at this point.

In the above described form of this invention, the hydraulic pump unit utilizes between 55 and 65 gallons per minute of fluid at 1250 to 2000 lbs. per square inch pressure and turning at 1800 to 2000 revolutions per minute. The mechanism provides approximately a 10 inch stroke of the hammer from 60 to 75 times per minute, thus delivering about 8400 foot pounds for each blow or slightly over 500,000 foot pounds per minute. The blow delivered is approximately four tons. The entire unit weighs about 1875 pounds.

A slight modification of the above device is indicated in FIG. 7 of the drawings. It should be understood that all parts previously described are the same except for the changes about to be indicated.

Power means is provided adapted for remote control whereby the tool 46 may be turned between different positions if desired by the operator. This is particularly useful where a chisel or the like is used for breaking up pavement or other ceramic material. In FIG. 7, a hydraulic motor 66 is indicated secured to the sleeve 61 in any suitable manner and supplied with hydraulic fluid through the conduit means 67. It is obvious that the conduits might be run back to the control cab where the operator of the boom 53 rides and there provided with control valves. Motor 66 through gear reduction 68 drives shaft 68a rotatably carried by bracket 68b. Rotatable with this shaft is small diameter pinion 69 which meshes with a larger diameter gear 70 which is secured to the anvil shaft 14 so as to turn this shaft and the tool 46 carried at the lower end thereof as shown in FIG. 1A. Gear 70 is held in position by collar 74 and pin 75. Spring 51' performs the same function as spring 51. By control of fluid to motor 66 the operator may slowly rotate tool 46, stopping it in any desired position.

What is claimed is:

1. A blow delivering device comprising a housing having first and second end walls with the axis of said housing passing through said end walls; a tool-carrying member having a shaft disposed coaxial with said housing and extending into said housing through said first end wall; said shaft having an enlarged, blow receiving anvil at its inner end disposed within said housing; a hammer reciprocatably mounted in said housing between said anvil and said second end wall; said hammer having an elongated extension coaxial with said shaft and extending through said second end wall; helical spring means telescoped over said extension and disposed between said hammer and said second end wall; power means carried by said housing outside of said second end wall and including means repeatedly retracting said extension and said hammer against the bias of said spring means and then suddenly releasing them in use of said device, thereby permitting said spring means to cause said hammer to deliver sequential blows against said anvil; resilient cushioning means disposed between said anvil and said first end wall and cushioning the blow of said hammer against said anvil portion; and additional cushioning means disposed between one end of said helical spring means and said hammer and between the other end of said helical spring means and said second end wall to cushion the blow of said hammer against said anvil.

2. A blow delivering device as set forth in claim 1; a collar secured to said shaft outside said housing and limiting the rebound of said anvil inwardly of said housing after each hammer blow; a coil spring surrounding said shaft and disposed between said collar and said first end wall to cushion the rebound of said anvil; said collar having means defining an aperture therein which is axially parallel with said shaft and laterally displaced therefrom; a bar secured to said housing and disposed parallel with

said shaft and projecting away from said housing in the direction of said collar, said bar slidably projecting through said aperture in said collar thereby preventing rotary movement of said shaft while allowing axial movement of said shaft.

3. A blow delivering device comprising a housing; a tool-carrying member having a shaft extending into said housing at one end thereof; said shaft having a blow receiving anvil portion disposed within said housing; a hammer reciprocatably mounted in said housing for a stroke movement in line with said shaft toward and away from said anvil portion; said hammer having an elongated extension coaxial with said shaft and extending further into said housing away from said hammer and out through the end of said housing opposite said one end; a helical spring means surrounding said extension and disposed between said hammer and said opposite housing end; power means carried by said housing including means repeatedly retracting said extension and said hammer against the bias of said spring means and then suddenly releasing them, in use of said device, thereby permitting said spring means to cause said hammer to deliver sequential blows against said anvil; and stop means carried by said member limiting the rebound movement of said anvil portion inwardly of said housing after each hammer blow; said stop means comprising a collar secured to said shaft outside said housing and limiting the movement of said shaft into said housing; said collar having means defining an aperture therein which is axially parallel with said shaft and laterally displaced therefrom; a bar secured to said housing and disposed parallel with said shaft and projecting away from said housing in the direction of said collar; said bar slidably projecting through said aperture in said collar thereby preventing rotary movement of said shaft while allowing axial movement of said shaft.

4. A blow delivering device comprising a housing; a tool-carrying member having a shaft extending into said housing at one end thereof; said shaft having a blow receiving anvil portion disposed within said housing; a hammer reciprocatably mounted in said housing for a stroke movement in line with said shaft toward and away

from said anvil portion; said hammer having an elongated extension coaxial with said shaft and extending further into said housing away from said hammer and out through the end of said housing opposite said one end; a helical spring means surrounding said extension and disposed between said hammer and said opposite housing end; power means carried by said housing including means repeatedly retracting said extension and said hammer against the bias of said spring means and then suddenly releasing them, in use of said device, thereby permitting said spring means to cause said hammer to deliver sequential blows against said anvil; and stop means carried by said member limiting the rebound movement of said anvil portion inwardly of said housing after each hammer blow; said stop means comprising a gear secured to said shaft outside said housing and limiting the movement of said shaft into said housing, a pinion rotatably mounted on said housing and meshing with said gear during axial movement of said shaft, and means controlling rotation of said pinion, whereby said gear and shaft may be held in fixed orientation or said shaft may be rotated about its own axis.
